UNITED STATES PATENT OFFICE.

ALBERT E. ALLAN, OF CANTERBURY, NEW ZEALAND.

REVERSIBLE BALLAST-SPREADING PLOW FOR RAILWAYS.

1,232,748.

Specification of Letters Patent. Patented July 10, 1917.

Application filed April 19, 1916. Serial No. 92,255.

To all whom it may concern:

Be it known that I, ALBERT E. ALLAN, a subject of the King of Great Britain, residing at Canterbury, New Zealand, have invented certain new and useful Improvements in Reversible Ballast-Spreading Plows for Railways, of which the following is a specification.

My invention relates to railway rolling stock and more particularly to an improved ballast spreading plow designed for use in railroad repair and structure work.

In describing my invention in detail reference will be had to the accompanying drawings wherein like characters denote like or corresponding parts throughout the several views, and in which:—

Figure 1 is a side elevation of a railway car equipped with my improved ballast spreading plow;

Fig. 2 is a plan view, partly in section, illustrating in detail the railway car construction and the arrangement of the plow parts with respect thereto;

Fig. 3 is a vertical longitudinal sectional view;

Fig. 4 is a horizontal longitudinal sectional view; and

Fig. 5 is a transverse longitudinal sectional view, enlarged, the movable plow parts being positioned as illustrated in Fig. 2.

Fig. 6 is a diagrammatic view illustrating the method of spreading the ballast employed by my machine.

Referring now to the drawings by numerals, 1 designates as an entirety a railway car equipped with my improved ballast spreading plow. The device of my invention in its preferred embodiment may be said to consist of a rectangular mold board supporting frame 2, opposed mold boards 3—3 coacting plow shares 4—4, an operating mechanism designated in its entirety by the numeral 5, whereby the opposed mold boards may be simultaneously moved into operative association with either of the plow shares 4, the latter, the plow shares 4, being located respectively (point foremost) at opposite ends of the mold board supporting frame 2.

A casting 6, vertically slotted as indicated at 7, is mounted intermediate the car ends to operatively support a control lever 8 shiftable to adjust the mold board 3 with respect to the plow share 4. One end of the lever 8 is bifurcated as indicated at 9 to straddle

an operating link 10 and coacting links 11. A pin 12 is carried by the lever 8 to penetrate the link 10 and operate in the slots 7 of the casting 6, the slots thus permitting vertical movement of the pin with respect to said casting yet precluding longitudinal movement of the lever with respect to the railway car 1.

Bars 13 brace the mold board supporting frame 2 and at the same time afford a means whereby the link 10 and the links 11 are fastened to said frame, a pivot pin 14 being utilized as the fastening means.

Rollers 15 are carried by the control lever 8, one at the end of each extension formed by the bifurcation aforesaid, the rollers engaging, as indicated in Fig. 5, with rails 16 extending in parallelism longitudinally of the car frame directly beneath the casting 6. Parallel longitudinally extending angle irons 17 (forming a part of the car chassis or frame) support the rail 16.

Studs 18 support the rollers 15, each stud being extended inwardly as indicated in Fig. 5 to engage and operate in slots 19 formed in the links 11.

A longitudinally movable carriage, designated as an entirety by the numeral 20, is mounted for movement beneath the angle irons 17 through action of the links 11. The carriage 20 in its preferred embodiment comprises opposed angle bars 21 vertically slotted as indicated at 22 and horizontally slotted as indicated at 23. Pins 24 carried by the links 11 engage and operate in the slots 22 that the carriage 20 may be moved in the manner stated, while pins 25 engage and operate in the slots 23 that the mold boards 3 may be shifted according to the movement of the mentioned carriage. Spaced parallel rails 26 support the carriage for movement.

Each mold board 3 is equipped with an arcuate operating arm 27 that movement may be transmitted thereto by movement of said carriage. The arm 27 carries the pin 25 which operates in the slot 23.

As indicated in Figs. 2 and 4, mold boards 3 are pivoted as indicated at 28 at opposite sides of the mold board supporting frame 2. By movement of the control lever 8 as indicated in Fig. 3, it is evident that the rollers 15 will ride upon the rail 16 and accordingly swing the links 11 at an angle to the vertical. The slots 7 and the slot 19 will limit movement of the lever 8, the rollers 15 and

the links 11 swing from one to the opposite side of a vertical dead center position, it is evident that the carriage frame will be accordingly moved. As 5 the carriage is moved from one to the opposite side of a dead center position, it is evident that the mold boards 3 will be likewise moved and accordingly swung into operative association with either the plow share 3 at one end of the supporting frame 2 or with the plow share 3 at the opposite end thereof. Each mold board is made to snugly and properly engage with the plow share 3 with which it is associated. A slot 10 15 29 is formed in the floor of the car 1 so that the lever 8, the link 10 and the links 11 may extend therethrough. The lever 8, if desired, may be equipped with a weight 30, mounted adjacent its handle end that the 20 said lever subsequent to adjustment will maintain and hold its adjusted position.

Movement and operation of the coacting elements in the manner stated, will, as the lever 8 is shifted, accordingly raise and 25 lower the mold board supporting frame 2 and consequently the plow share 4 and the mold board 3 carried thereby. As the said lever 8 is swung from an angular position to a vertical dead center position, and since 30 the rollers 15 are incapable of vertical movement, vertical movement of the pin 12 in the slot 7 will occur. Since the link 10 is fastened at one end to the said pin 12, it is further apparent that the links will be raised 35 and by reason of the connection indicated at 14, the mold board supporting frame 2 accordingly raised.

As a means whereby the said control lever may be locked in a true vertical position, I 40 provide opposed latch bars 31. Each latch bar is mounted in a slot 32 therefor formed in the casting 6. Spring retaining devices 33 fastened as at 34 to the casting 6 engage with and maintain the latch bars 31 in engagement with the control lever to thus releasably fasten the said lever in said vertical position. As indicated, the latch bars 31 engage with the opposite longitudinal edges of the control lever.

50 From the foregoing, taken in connection with the accompanying drawings, it is evident that the mold board supporting frame 2 and the plow shares 4 and the mold boards 3 carried thereby, may be lowered from the 55 position illustrated in Fig. 5 to a position in contact with the railway rail as illustrated in Fig. 3, the parts thus lowered functioning to spread the ballast evenly between and at opposite sides of the railway rails. 60 Guides 2^a and 2^b may be mounted on the car body and frame 2 respectively for guiding the frame 2 in its vertical movement. It is further evident that the mold board may be reversed through manipulation of 65 the control lever 8 to coöperate with the

plow shares 4 at either end of the mold board supporting frame that the ballast may be spread in the manner described regardless of the direction of movement of the railway car acting as the plow support. In 70 Fig. 6 of the drawings I have illustrated diagrammatically, a mold board 3^a which is provided at its lower edge with a recess 3^b which is adapted to receive the ball of the rail so as to dispose the lower edge of 75 the mold board below the upper surface of the rail, in order that the ballast may be leveled and not be engaged by the flanges of the car wheels.

In reduction to practice, I have found that 80 the form of my invention, illustrated in the drawings and referred to in the above description, as the preferred embodiment, is the most efficient and practical; yet realizing that the conditions concurrent with the 85 adoption of my device will necessarily vary, I desire to emphasize the fact that various minor changes in details of construction, proportion and arrangement of parts may be resorted to, when required, without sacrificing any of the advantages of my invention, as defined in the appended claims.

Having thus fully described my invention, what I claim as new and desire to secure by Letters Patent, is:—

95 1. In a ballast spreading device for railway repair and construction work, a supporting frame movable toward and from the railway rails, a plow share at each end of the frame, a mold board at each side of the 100 frame, the mold boards being reversible for coöperation with either plow share, and a means to simultaneously vertically adjust the supporting frame and reverse the position of the mold boards with respect to the 105 coöperating plow shares.

2. In a ballast spreading device for railway repair and construction work, relatively fixed plow shares, opposed reversible mold boards, and a single manually operable 110 means to simultaneously reverse the mold boards to provide for coöperation of the said mold boards with either of the mentioned shares.

115 3. In a ballast spreading device for railway repair and construction work, relatively fixed plow shares, opposed mold boards mounted for turning movement into endwise engagement with either of the plow shares, and a means to lower the plow structure thus formed into engagement with the 120 railway rails in the manner stated.

125 4. In a ballast spreading device for railway repair and construction work, a vertically movable supporting frame, plow shares mounted at opposite ends of the frame, mold boards mounted at opposite sides of the frame for oscillatory movement for permitting endwise engagement thereof with either plow share, and a means movable in a straight 130

line engaging the opposed mold boards to reverse the position of said mold boards and accordingly permit of coöperation with either end plow share.

5. In a ballast spreading device for railway repair and construction work, a supporting frame, mold boards mounted for turning movement at opposite sides of the frame, a carriage engaging with the opposed mold boards and moving longitudinally of the supporting frame to vary the position of the mold boards with respect thereto, and a lever operable to move the carriage in the manner stated.
10. In a ballast spreading device for railway repair and construction work, a supporting frame, a mold board mounted at each side of said frame, a carriage mounted to engage with the opposed mold boards,

- 20 rails supporting said carriage for movement longitudinally of the supporting frame, and a lever operable to move said carriage in the manner stated to vary the position of the mold boards with respect to 25 said supporting frame.

7. In a ballast spreading device for railway repair and construction work, a supporting frame, opposed relatively movable mold board structures, mounted, one on each 30 side of said frame, a carriage movable longitudinally of said supporting frame and engaging with the opposed mold board structures to vary the position of said structures with respect to the frame, and a means 35 engaging said carriage to raise and lower the supporting frame and the mold board structures carried thereby during adjustment of the latter in the manner stated.

8. A ballast spreading device for railway 40 repair and construction work including a supporting frame, opposed relatively movable mold board devices, a carriage mounted to engage with the opposed mold board devices, and a means engaging said carriage 45 to move it longitudinally of the supporting frame to vary the position of the mold board devices with respect thereto and at the same time raise and lower said mold board devices respectively out of and into engagement with 50 the railway rails.

9. In a ballast spreading device for railway repair and construction work, a supporting frame, a plow structure carried by said frame, a control lever, a connection between 55 said lever and said supporting frame, rollers mounted at one end of said lever, guide rails with which the rollers engage, said control lever being movable from a dead center vertical position to a position at an angle to the 60 vertical that the supporting frame may be moved either out of or into engagement with the railway rails, and a means to maintain said lever in its dead center vertical posi-

tion to accordingly maintain the said plow structure out of engagement with the railway rails.

10. In a ballast spreading plow for railway repair and construction work, a supporting frame, a plow structure carried by said supporting frame, a control lever movable from a dead center vertical position to a position at an angle to the vertical at either side of said vertical position to raise and lower the plow structure respectively out of and into engagement with the railway rails, 75 a connection between said lever and said supporting frame, a means to limit vertical movement of said supporting frame during adjustment of the plow structure in the manner stated, and a means to maintain the 80 lever in a dead center vertical position to accordingly maintain the plow structure out of engagement with the railway rails.

11. In a ballast spreading device for railway repair and construction work, a supporting frame, a plow share mounted at each end of the frame, a mold board device mounted at each side of the frame, and a means to simultaneously reverse the position of the mold board devices for the purpose 90 specified.

12. In a ballast spreading device for railway repair and construction work, a supporting frame, a plow share at each end thereof and oscillatably mounted mold 95 boards at each side of the frame adapted for endwise engagement with either plow share and a means to simultaneously move the mold board and vertically adjust said supporting frame so that the mold board in the 100 lowermost position of the frame may engage with the railway rails.

13. In a ballast spreading device, for railways, the combination of a wheel supported truck, a plow structure supported beneath 105 said truck, including a frame, a plow share mounted at either end thereof, mold boards mounted at opposite sides of the frame for oscillation and for endwise engagement with either plow share, a means movable in one 110 direction or the other to lower the plow structure, said operating means being operable to raise the plow structure when moved to an intermediate position, and means operable by movement of said operating means 115 in one direction or the other as aforesaid to oscillate the mold boards to engage the same with one plow share or the other as the case may be.

In testimony whereof I affix my signature 120 in presence of two witnesses.

ALBERT E. ALLAN.
